(No Model.)

C. N. ROBERTS.

PRINTING ATTACHMENT FOR ROTARY PRINTING MACHINES.

No. 417,509.

Patented Dec. 17, 1889.

UNITED STATES PATENT OFFICE.

CHARLES N. ROBERTS, OF CHICAGO, ILLINOIS.

PRINTING ATTACHMENT FOR ROTARY PRINTING-MACHINES.

SPECIFICATION forming part of Letters Patent No. 417,509, dated December 17, 1889.

Application filed November 3, 1888. Serial No. 290,062. (No model.)

To all whom it may concern:

Be it known that I, CHARLES N. ROBERTS, a citizen of the United States, and a resident of Chicago, in the county of Cook and State 5 of Illinois, have invented a certain new and useful Improvement in Printing Attachments for Rotary Printing-Machines, of which I declare the following, together with the accompanying sheet of drawings, to be a full, complete, and accurate specification.

My improvement relates to that class of printing-machines upon which newspapers are printed from a roll of white paper, and usually known as "high-speed-cylinder news 15 paper - printing presses," my improvement forming an adjunct thereto whereby the margin of the paper may be utilized and printed upon, as well as the body thereof.

In the operation of printing newspapers 20 upon presses of this kind it is necessary that a blank margin of about one inch be allowed to remain upon either side of the sheet of paper as it enters the press from the roll, in order that the tapes and grippers may engage the same in the operation of carrying 25 the sheet through the press. This said blank margin, on account of its specially-prominent position, would be, if utilized for advertising purposes, of great value.

My said improvement consists of such 30 mechanism as may print any desired matter, in any desired color, upon the margin usually left blank, (for the reasons aforesaid,) as the paper is unrolled before entering the press, 35 thus leaving the margin thus printed free to be engaged, operated upon, or held by the tapes or other engaging part of the press while the paper is passed through the press and the body thereof printed upon in the 40 usual manner. The mechanism which I use to attain this end consists of a narrow-faced cylinder, (the thickness thereof conforming to the width of margin to be printed,) upon which may be engraved the characters which 45 it is desired to print upon said margins, or upon which may be affixed movable types or plates of rubber, metal, or other substance capable of transmitting a legible impression upon paper. This cylinder is equipped with 50 inking apparatus, governing and operating appliances, as hereinafter described, and af-

fixed to the press at such desirable point that it may operate upon and print characters desired upon the margin of the paper before the same is engaged by any of the mechanism 55 of said press operating as aforesaid upon said margin.

The construction and operation, as well as the individual and combined utility of the several parts of my said invention, may be 60 better shown and described by reference to the accompanying sheet of drawings, which is hereby made a part of this specification.

Upon the said sheet of drawings, Figure 1 shows a side elevation of a portion of the 65 foot-plate or shoe of a cylinder printing-press, the journal-bracket and paper-cylinder thereon, and attached thereto my improvement, the subject of this specification. Fig. 2 shows a longitudinal elevation of paper roller with 70 my improvement thereon, shown in vertical section. Fig. 3 is a vertical section showing the constructional features of the inking device I use upon my invention. Fig. 4 is a top plan of one of the constructional elements of 75 my invention, which is designated by letter O, and is hereinafter fully described.

In the several figures like letters of reference indicate like parts.

A is a roll of print-paper upon a core E, operating in journal-boxes placed at convenient position at the rear end of a printing-press. As the paper is drawn into the press it unrolls by the revolution of the roll in direction indicated by the arrow thereon.

B is a portion of the shoe or foot-plate of a printing-press resting upon the floor.

C C are the end supports, upon which the journal-boxes are placed to hold the journal-shaft of roller-core E.

D D are the journal-boxes placed, respectively, upon the supports C C.

E is the shaft of the paper-roll core, and is journaled at its respective ends in the journal-boxes D D.

F is a narrow-faced cylinder, upon the face of which may be engraved or affixed types, cuts, or dies capable of printing an impression when impressed upon paper, and is placed in such relative position to the paper roll that its face bears upon the margin of the paper.

H H' are two uprights placed, respectively, on either side of printing-cylinder F, and each bored to receive the journal-shaft of said cylinder. The lower ends of these uprights 5 are severally weighted, as indicated by M, with sufficient heft to swing them by gravity upon the loose journal-shaft of cylinder F, and then cause them by gravity to assume and retain a vertical position, the upper parts 10 of said uprights extending upward a short distance above the topmost point of the circumference of said cylinder F. Journaled into these said uprights, above the cylinder F, are two ink-rollers I and L, being respectively 15 a distributive roller and an inking-roller for the surface of cylinder F, and supported at the upper extremity of said uprights is an ink-supply fountain P.

I and L are respectively the distributing 20 and inking rollers above referred to, placed between and journaled into the uprights H and H', the face of the lower or inking roller L resting upon the face of printing-cylinder F, and the upper or distributing roller I engag- 25 gaging the upper surface of inking-roller L.

M indicates the lower or weighted end of upright H.

N is an upright arm extending from any 30 convenient part of the press-frame to a point about even with the top of the paper roll when full.

O is an extension affixed by a pivoted joint to the upper end of arm N, the end of extension O being in the shape of a fork, as shown 35 specifically in Fig. 4. The ends of the fork are bored to form bearings for the journal-shaft of cylinder F, which said cylinder and the uprights H and H' are placed to operate in said fork.

40 P is the ink-fountain above referred to, and is fixed at the upper end of the said uprights H and H'.

R indicates a valve in fountain P, whereby 45 the flow of ink from said fountain to distributing-roller I may be regulated and governed.

T indicates the point at which the extension O is affixed to the arm N, as aforesaid.

In the operation of my invention as above 50 constructed the extension O of arm N, in the fork of which is journaled the printing-cylinder F, is bent over at the joint, so that the circumferential face of cylinder F comes in contact with the outer margin of the paper- 55 forming roll A.

55 In the operation of the printing-press the paper on roll A is drawn inward to be printed from the roll in the direction and manner indicated by A' and the arrow placed near the ex- tended sheet shown in Fig. 1. Ink flows from

60 fountain P through valve R to distributing- roller below, from thence to inking-roller, and

is then and therefrom imparted to the characters engraved upon or affixed to the face of the printing-cylinder F. As the paper is drawn into the press, as aforesaid, the roll A 65 is revolved in the direction indicated by the arrow placed thereon. As the face of printing-cylinder F bears, as aforesaid, frictionally upon the margin of the paper in said roll and is there held by its own weight, as 70 assisted by the suspended weight M, and, consequent upon the revolution of said cylinder-roll A, cylinder F is correspondingly revolved by frictional contact and an impression of the characters engraved or affixed to the sur- 75 face thereof is imprinted therefrom upon the margin of the said paper upon the said roll. It is intended that the circumference of the printing-cylinder F shall equal the length of the sheet of each newspaper, whereby the 80 impressions printed at each revolution of said cylinder may be caused to appear upon the margin of each newspaper printed, and as the printing-cylinder F is suspended upon the extended arm O, playing upon pivot-joint T, 85 the said cylinder by force of gravity hugs the roll of paper, and as the roll of paper de- creases in size by its expenditure the said ex- tension of arm O so governs the said print- 90 ing-cylinder that it constantly holds the same relative position to the roll as it decreases and continually sustains its frictional rela- 95 tion thereto, whereby it imparts the imprint of its surface to the margin of the decreasing roll.

Having in the hereinbefore manner and form described the component parts, their 100 respective utility, the combinations thereof, and also the utility and general construction of my said improvement, I therefore claim as my invention—

Upon a printing-press printing from a roll of paper, a narrow printing-cylinder so placed as to engage the outer margin of the paper upon said roll, and in combination therewith an inking apparatus consisting of inking roller or rollers and ink-fountain affixed to two upright parts, said upright parts being suspended from the journal-shaft of said cylinder and having their lower end weighted with sufficient weight to cause the said upright parts to assume and continually retain a vertical position, all as above described, set forth, and specified.

In witness whereof I have hereunto affixed 115 my signature at Chicago, aforesaid, in the presence of two subscribing witnesses, this 20th day of October, 1888.

CHARLES N. ROBERTS.

In presence of—

W. KNOX HAYNES,

CHARLES T. BLACKWELL.
